UNITED STATES PATENT OFFICE.

WILLIAM GERRARD, OF BLACKBURN, ENGLAND, ASSIGNOR TO DRAPER COMPANY, OF HOPEDALE, MASSACHUSETTS, A CORPORATION OF MAINE.

TEMPLE-CUTTER FOR AUTOMATIC WEFT-REPLENISHING LOOMS.

1,128,440.

Specification of Letters Patent. Patented Feb. 16, 1915.

Application filed April 23, 1913. Serial No. 762,989.

To all whom it may concern:

Be it known that I, WILLIAM GERRARD, a subject of King George V of Great Britain, residing at Blackburn, in the county 5 of Lancaster, England, have invented certain new and useful Improvements in or Relating to Temple-Cutters for Automatic Weft-Replenishing Looms, of which the following is a specification.

10 This invention relates to automatic looms for weaving in which a temple thread cutter is employed for cutting off from the edge of the cloth, loose ends of which are existent after a change or transfer of cop or bobbin. 15 In the majority of looms of this class the temple thread cutter works continuously with the result that it quickly becomes worn to a sufficient extent to render it dull and inoperative and the present invention 20 has for its object to provide improved means to relieve the temple thread cutter from unnecessary wear so that it will remain in good condition for a considerable period.

According to this invention, the cutter 25 arm, or part that actuates the cutter is connected with a device controlled by the cop or bobbin changing mechanism normally to retain the cutter stationary and out of operation but to be brought into action at every 30 transfer or change of cop or bobbin and to be retained in action for a sufficient number of picks to insure the cutting of the thread or threads.

The manner in which the invention is put 35 into practice will be described with reference to the accompanying drawing, in which:—

Figure 1 is a sectional end elevation of such parts of an automatic loom as are necessary 40 for the explanation of the improvements, of which one embodiment is shown applied, while Fig. 2 is a corresponding view to Fig. 1, but shows some of the parts in different positions.

45 Referring to the drawing, 1 represents the temple thread cutter, which is mounted as usual to occupy a position adjacent the selvage of the fabric, being carried by a suitable bracket 2 attached to the breast beam 3 of the loom. The temple thread cutter comprises a stationary cutting blade 4 and a movable cutting blade 5, the latter having a depending heel or arm 6 from which projects a pin 7 around which is coiled one end 50 55 of a spring 8 whose opposite end is coiled

around a pin 9 carried by the cutter head 1. The spring 8 tends to normally hold the movable cutting blade 5 in the position shown in Fig. 2 in which position the heel or arm 6 can be engaged, at each beat up 60 of the lay 10, by an abutment 11 thereon, to cause the movable cutting blade to be actuated in the usual and well known manner.

12 represents the usual rock shaft by 65 which the transfer mechanism is operated in the well known Northrop loom, to effect weft replenishment when called for, and 13 represents the usual taking-up or roughened roller around which the fabric 13' passes to 70 be wound on to the cloth beam 14.

According to my invention, the heel or arm 6 of the movable cutting blade is connected by a suitable attachment 15 passing in this instance over the breast beam 3 with 75 a barrel, pulley, cam, eccentric, or the like 16 rigidly connected with a mutilated pinion 17 pivotally carried by an arm 18 fast on the rock shaft or changing shaft 12. The pinion 17 has a flat 17' on one portion 80 of its periphery, and a toothed portion 17², and the connection 15 acts under the influence of the spring 8 to rotate the pinion, when the latter is free to move, to present the toothed portion of the pinion to the 85 teeth of a gear 19 rotating with the take-up roller 13. The disposition of the arm 18 on the rock shaft 12 is such that when the said arm moves back to normal position after being operated to bring about weft 90 replenishment, it carries the toothed portion 17² of the pinion 17 into mesh with the teeth of the gear 19. The pinion is thus rotated for a certain time until the flat 17' on the mutilated pinion is brought opposite 95 to the teeth of the gear 19 as shown in Fig. 1, whereupon its rotation ceases. The partial rotation of the pinion 17 and thus of the barrel, pulley, cam eccentric or the like 16 causes the connection 15 to gradually 100 draw the heel or arm 6 of the movable cutting blade forward to such a position that it is clear of the usual abutment 11 on the lay when the latter is in its forward position as in Fig. 1, so that the said cutting blade 105 remains stationary. When the rock shaft 12 is partly turned, in the direction of the arrow A, Fig. 1, to effect weft replenishment, the pinion 17 is carried clear of the teeth of the wheel 19 and the spring 8 re- 110

turns the movable cutting blade 5 to operative position as shown in Fig. 2, on which it will be engaged by the abutment 11 at each forward beat of the lay. The partial 5 rotation of the pinion 17 occasioned by the return of the movable cutting blade to operative position presents the toothed portion 17² thereof to the teeth of the gear 19 so that as the rock shaft moves back after replenishment the said pinion reengages with the gear 19 and is again rotated to gradually withdraw the heel of the movable cutting blade out of the reach of the abutment. A stop 20 on the pulley or the like 16 is adapted to engage the arm 18 to limit the extent of rotation of the pinion 17 under the pull of the connection 15.

By the means above described, the temple 20 thread cutter is only permitted to operate for a pre-determined time after each replenishing action, that is to say, for such a time as will insure the cutting of the end of filling, left by the exhausted bobbin, extending from the selvage of the fabric.

25 The details of construction and arrangement of the improvements may be varied, for example in some cases it may be convenient to control the withdrawal of the movable cutting blade from some part of 30 the changing mechanism other than the rock shaft.

Having thus described my invention, what I claim as new and desire to secure by Letters Patent is:—

35 1. In an automatic weft-replenishing loom provided with a temple thread cutter actuated by or through the movement of the lay, the combination of means controlled by or through the changing mechanism of the 40 loom to place the cutter in actuating position, and means controlled by or through the take-up roll for throwing the cutter out of actuating position after a predetermined period.

2. In an automatic weft-replenishing loom 45 a temple thread cutter having a stationary blade and a movable blade, an actuator connected with the movable blade and adapted to actuate it upon and through the beat-up on the lay, a spring acting to move the actuator into the path of the lay, a movable arm, a mutilated pinion on said arm, a connector extending from said actuator to said pinion, a gear constantly driven and means actuated upon the call for filling replenishment to 50 move said arm to carry the pinion away from the gear and allow the spring to act and thereafter to move said arm to bring the pinion into coöperation with the gear and cause the actuator to be withdrawn 55 from the path of the lay after a predetermined period.

3. In an automatic weft-replenishing loom 60 a temple thread cutter having a stationary blade and a movable blade, an actuator 65 connected with the movable blade and adapted to actuate it upon and through the beat-up on the lay, a spring acting to move the actuator into the path of the lay, a movable arm, a mutilated pinion on said arm, a 70 flexible connector extending from said actuator around the breast beam to said pinion, a gear constantly driven and means actuated upon the call for filling replenishment to move said arm to carry the pinion away 75 from the gear and allow the spring to act and thereafter to move said arm to bring the pinion into coöperation with the gear and cause the actuator to be withdrawn from the path of the lay after a predetermined 80 period.

In testimony whereof I affix my signature in the presence of two witnesses.

WILLIAM GERRARD.
